UNITED STATES PATENT OFFICE

KURT RETTICH, OF TOLEDO, OHIO, ASSIGNOR, BY MESNE ASSIGNMENTS, TO THE REYNOLDS SPRING COMPANY, OF JACKSON, MICHIGAN, A CORPORATION OF DELAWARE

DESIGN FOR A COMBINED CORKSCREW AND GUARD

Application filed May 31, 1932. Serial No. 43,943. Term of patent 3½ years.

To all whom it may concern:

Be it known that I, KURT RETTICH, a citizen of the United States of America, residing at Toledo, in the county of Lucas and State of Ohio, have invented a certain new, original, and ornamental Design for a Combined Corkscrew and Guard, of which the following is a specification, reference being had therein to the accompanying drawing, forming a part thereof, in which—

Figure 1 is a perspective view of a combined cork screw and guard showing my new design, and Figure 2 is a front elevation thereof.

A dominant feature of my design consists in the representation of an animated creature forming a handle.

Another dominant feature of my design, which may or may not be used, consists in providing the cork screw and the guard with different or contrasting colors, as indicated by the shading.

I claim:

The ornamental design for a combined cork screw and guard substantially as shown and described.

KURT RETTICH.
